James Bowers,

BY Drake & Co. ATTYS.

UNITED STATES PATENT OFFICE.

JAMES BOWERS, OF NEWARK, NEW JERSEY.

DESIGN FOR A CORSET.

SPECIFICATION forming part of Design No. 17,126, dated February 22, 1887.

Application filed July 2, 1886. Serial No. 206,919. Term of patent 7 years.

To all whom it may concern:

Be it known that I, JAMES BOWERS, a citizen of the United States, residing at Newark, in the county of Essex and State of New Jersey, have invented and produced a new and original Design for Corsets; and I do hereby declare the following to be a full, clear, and exact description of the invention, such as will enable others skilled in the art to which it applies to make and use the same, reference being had to the accompanying drawings, and to letters of reference marked thereon, which form a part of this specification.

In the drawings, Figures 1, 2, and 3 are side elevations of corsets embodying the design, showing variations therein.

The corset-shaped in accordance with the design, when viewed in side elevation, presents to view a vertical section or panel, A, extending from the top to the bottom of the corset. At the sides of this section, which is substantially of uniform width from the top to the bottom of the corset, and is uninterrupted in its extension by crossing panels or ornamentation, are panels B B, of transverse ornamental stitching, which lie at about the middle of the waist portion of the corset and show their lines of ornamental stitching as extending at right angles to the vertical section or panel A, so that the lines in the opposite panels are in straight or direct lines, those of the one with those of the other, their courses not being at angles. Said panels B B lie between uppermost and lowest panels or sections, C C D D, which are also laterally adjacent to the mid section or panel, A. Said uppermost and lowest panels, C C D D, are flaring in shape, being narrower where they border the central sections or panels, B B, and wider toward the upper and lower

edges of the corset, respectively. Said sections present a surface to view which is dissimilar in ornamentation to that of the central sections, B B. In the lowest sections D D the ornamental lines are not displayed over the whole of their respective surfaces, but appear to extend longitudinally through the central portions of the said sections, thus presenting central ornamental sections, E, and lateral panels or sections F.

The essential feature of the design consists in a corset presenting the appearance, configuration, and ornamentation shown and described, and

What I claim as new is---

The design for a corset, which consists, essentially, in a corset which presents to view on the outer face thereof a vertical panel, as A, extending from the bottom to the top of the corset, and at the opposite sides of said vertical panel ornamental central sections or panels, B B, with lines extending at right angles to said vertical section, and panels C C and D D, displayed above and below said central panels and on opposite sides of said vertical panel, the sections D D presenting narrow borders to the central sections and wider borders to the lower edge of the corset, and displaying central ornamentation, E, and sections or panels F at the sides thereof, all substantially as set forth.

In testimony that I claim the foregoing I have hereunto set my hand this 18th day of June, 1886.

JAMES BOWERS.
